UNITED STATES PATENT OFFICE.

GARRET D. MARVIN, OF FINDLAY, OHIO.

GAS-ENGINE VALVE.

1,261,420.

Specification of Letters Patent.

Patented Apr. 2, 1918.

Application filed September 15, 1917. Serial No. 191,628.

To all whom it may concern:

Be it known that I, GARRET D. MARVIN, a citizen of the United States, residing at Findlay, in the county of Hancock and State 5 of Ohio, have invented a new and useful Gas-Engine Valve, of which the following is a specification.

The present invention appertains to valves for engines, and aims to provide a novel and 10 improved valve structure embodying a rotary valve member, to control the intake and exhaust without the liability of leakage or other objections incident to the use of puppet valves and the like.

15 It is the object of the invention to provide a valve structure of the nature indicated comprising a novel construction and assemblage of the component elements, whereby the device will be practical and efficient in 20 use.

With the foregoing and other objects in view which will appear as the description proceeds, the invention resides in the combination and arrangement of parts and in 25 the details of construction hereinafter described and claimed, it being understood that changes in the precise embodiment of the invention herein-disclosed can be made within the scope of what is claimed, without de- 30 parting from the spirit of the invention.

The invention is illustrated in the accompanying drawings, wherein—

Figure 1 is a diametrical section of the valve, taken on the line 1—1 of Fig. 2.

35 Fig. 2 is a cross section on the line 2—2 of Fig. 1.

Fig. 3 is a diametrical section on the line 3—3 of Fig. 2, portions being broken away.

Fig. 4 is a bottom plan view, a portion of 40 the valve disk or member being broken away to show the ports.

In carrying out the invention, there is provided a flat or disk-shaped head 1 to rest against the outer end of the engine 45 cylinder 2, and said head is provided with an outstanding outer dome or jacket 3, and a marginal outstanding flange 4 which can be bolted or otherwise fastened to the water jacket 5 of the cylinder 2, similar to the 50 head of an ordinary engine cylinder. The head 1 is provided within the dome or jacket 3 with an inner outstanding dome or casing 6 spaced from the walls of the jacket 3 to provide a water space 7 within the jacket 55 3 surrounding the casing 6 and extending over the top thereto. The head 1 has ports

8 therein leading to the water space 7 between the jacket 3 and casing 6 and adapted to communicate with the water space 9 of the water jacket 5, for the flow of water 60 from the space 9 into the space 7 to cool the valve structure, the jacket 3 having a water outlet port 10 for the flow of water to the radiator after passing around the casing 6.

United with the head 1, casing 6 and jacket 3 centrally thereof, is a tubular bearing or member 11, and the head 1 has a depending inwardly extending annular flange or apron 12 to fit snuggly within the cylinder 2 when 70 the head is attached thereto. Diametrically opposite radial partitions 13 are provided within the casing 6, being united with said casing, head 1 and bearing 11, to divide the interior of the casing into opposite arcuate 75 chambers 14, one of which is an intake chamber and the other an exhaust chamber. The walls of the jacket 3 and casing 6 have united therewith, the opposite tubular members 15 providing intake and exhaust ports 80 communicating with the chambers 14 through the water space 7 which surrounds the said tubular members. The head 1 has ports 16 at opposite sides of one partition 13 and communicating with the two chambers 14 85 for the flow of the carbureted air into and the products of combustion out of the cylinder.

A rotary shaft 17 is journaled through the bearing 11, and a rotatable valve member or disk 18 is fitted upon said shaft against the head 1 within the apron 12, and is provided with a port 19 to register in succession with the ports 16. The ports 16 are so arranged, that when the port 19 registers 90 therewith in succession, this will provide for the intake of carbureted air into and the exhaust of the products of combustion from the cylinder at the proper time. The disk 18 in fitting against the head 1 will close 100 the ports 16 excepting when the port 19 registers therewith. The valve disk 18 has a hub 20 secured by means of a pin or otherwise to the shaft 17, said hub extending away from the head 1. The valve disk 18 105 is rotated in proper timed relation with the crank shaft (not shown) to provide for the proper intake and exhaust of gas.

In order to keep the valve disk lubricated, a lubricant tube 21 extends through the tops 110 of the jacket 3 and casing 6 and through the head 1 to a radial lubricant groove 22

provided in the lower side of the head. Lubricant can be supplied into the tube 21 from a lubricant cup 22 attached to the upper or outer end thereof, and the lubricant flowing into the groove 22 will be spread onto the upper surface of the valve disk 18. The valve disk in rotating, will therefore be lubricated, and the valve will require no grinding, due to the continued rotation thereof. The deposit of carbon will therefore not cause the valve to leak, and it will therefore perform its function in a satisfactory manner.

The means illustrated for rotating the shaft 17, embodies a worm wheel 24 feathered, as at 25, on the shaft 17, and suitable anti-friction means 26 can be provided between the worm wheel 24 and top of the jacket 3, if desired. A coiled wire expansion spring 27 is confined between the worm wheel 24 and a nut 28 adjustable on the shaft 17, whereby to hold the worm wheel against the jacket 3, and to yieldably move the shaft 17 outwardly, whereby to hold the valve disk 18 seated against the head 1 snugly. The jacket 3 has a bracket 23 to which the

outer terminal of the shaft 17 is journaled, and a drive shaft 30 is journaled through the bracket 23 and carries a worm 31 meshing with the worm wheel 24 to rotate the valve shaft or stem 17.

Having thus described the invention, what is claimed as new is:—

An engine valve embodying a head having an outstanding casing, a tubular bearing united with said casing and head, partitions within the casing and providing intake and exhaust chambers therein, the casing and head having intake and exhaust ports communicating with said chambers, a shaft extending through the bearing, an apron on the head and adapted to enter an engine cylinder, and a valve disk carried by the shaft turning within the apron and bearing against the head to control the ports thereof.

In testimony that I claim the foregoing as my own, I have hereto affixed my signature in the presence of two witnesses.

GARRET D. MARVIN.
